199,921

TABLE GAS LIGHTER FOR CIGARETTES AND THE LIKE

Shinjiro Kobayashi, Edogawa-ku, Tokyo, Japan, assignor to Mansei Kogyo Kabushiki Kaisha, Kawaguchi-shi, Saitama, Japan

Filed Nov. 22, 1963, Ser. No. 77,540

Term of patent 14 years

(Cl. D48—27)

FIG. 1 is a front elevational view of a table gas lighter for cigarettes and the like showing my new design;

FIG. 2 is a rear elevational view thereof;

FIGS. 3 and 4 are elevations as seen from the left and right, respectively, of FIG. 1; and FIGS. 5 and 6 are top and bottom plan views respectively.

I claim:

The ornamental design for table gas lighter for cigarettes and the like, substantially as shown.

References Cited by the Examiner

UNITED STATES PATENTS

D. 76,363	9/29	Tennhardt	-----	D48—27
D. 85,635	12/31	Cohen	-----	D48—27
D. 98,136	1/36	Berthold	-----	D48—27

WALLACE R. BURKE, Acting Primary Examiner.